[57] **CLAIM**

The ornamental design for a combination stylus and pen, as shown and described.

DESCRIPTION

FIG. 1 is a right rear perspective view of a combination stylus and pen showing our new design;

FIG. 2 is a front elevational view;

FIG. 3 is a side elevational view, the opposite side being a mirror image thereof;

FIG. 4 is a rear elevational view;

FIG. 5 is a bottom plan view;

FIG. 6 is a top plan view;

FIG. 7 is an enlarged fragmentary rear perspective view;

FIG. 8 is a view of FIG. 7 with the writing tip extended;

FIG. 9 is a second enlarged fragmentary rear perspective view;

FIG. 10 is a view of FIG. 9 with the writing tip extended;

FIG. 11 is an enlarged top and side perspective view of the upper portion of the combination stylus and pen; and,

FIG. 12 is a front perspective view of FIG. 11.
